United States Patent Office.

JOHAN LINNEMANN, OF COPENHAGEN, DENMARK.

Letters Patent No. 92,978, dated July 27, 1869.

IMPROVEMENT IN TURRETS FOR VESSELS.

The Schedule referred to in these Letters Patent and making part of the same.

To all whom it may concern:

Be it known that I, JOHAN LINNEMANN, of Copenhagen, in the Kingdom of Denmark, have invented a new and useful Improvement in Turrets for Iron-Clad Vessels; and I do hereby declare the following to be a full, clear, and exact description of the same, reference being had to the annexed drawings, making a part of this specification, in which—

Figure 1 is a side elevation of an iron-clad vessel, showing the adjustable turrets in a position extending above the deck.

Figure 2 is a top view of an iron-clad vessel, showing three adjustable turrets.

Figure 3 is an elevation of an adjustable turret, constructed to shelter one sentry.

Figure 4 is an elevation of an iron-clad turret, constructed to shelter two or more sentries, and showing a device for raising or lowering the adjustable turret.

The same letters of reference, in all the figures, denote identical parts.

My invention consists in providing iron-clad vessels with one or more adjustable turrets or iron-clad sentry-boxes, the turrets being so constructed that they may be partly elevated above the upper deck of the vessel, or lowered so much that the top of the adjustable turret is on a level with the upper face of the deck.

These adjustable turrets are provided for the purpose of protecting sentries against the bullets of an enemy, and thereby preventing the enemy, by a surprise, from boarding the iron-clad and taking possession of the upper deck.

To enable others skilled in the art to make and use my improvement, I will proceed to describe its construction and operation.

A is an iron-clad vessel, with one large gun-turret, B.

D is a smoke-stack.

E, F, and G, are adjustable turrets, placed in such position that the sentries within, with their muskets, can hit any person on the upper deck.

H is a cover for hatchway, projecting above the deck.

Fig. 2 shows three adjustable turrets, E, F, and G. The dotted lines indicate the direction in which shots may be fired from these adjustable turrets.

Shots fired from the turret G, in front of the large gun-turret B, will prevent the enemy from boarding the deck on this part of the vessel; and the shots fired from the turrets E and F, will prevent the boarding of any part of the vessel back of the gun-turret B.

If the iron-clad vessel has more than one large gun-turret, more minor turrets or adjustable sentry-boxes are needed, in order to have a clear sweep over the deck.

The minor turrets must then be placed in such rel-

ative position to each other that sentries placed within them may be able to kill any person boarding the upper deck; the object being to place the turrets so that neither the large gun-turret, nor any other projecting object on the upper deck, may serve as shelter for the enemy trying to take possession of the deck.

Fig. 3 represents a minor turret or sentry-box, in which one sentry may be posted.

The turret E is constructed in such a way that the upper part of its wall is built in a substantial way, and the outside covered with iron plates, in order to prevent any shot fired against it from penetrating.

This upper part of the turret is provided with a suitable number of oblong apertures, I", which may be opened or closed, by means of shields or movable circular plates attached to the inside of the turret.

These apertures I" may be large enough to admit one or two muzzles of fire-arms. (Short breech-loading rifles are proposed.) There may be two movable circular plates or shields, one above the other, so arranged that two sentries may fire through the same aperture I" at the same time; or if only one muzzle is placed in the aperture, then the shield will cover half the opening. By such arrangement, the sentry or sentries placed in the turret are less liable to be shot by a surrounding enemy.

The lower part of the turret is constructed with vertical supports K K K, &c., on which the top part rests. These supports K, &c., are placed so far from each other that a man can pass between them, and have an easy ingress and egress to and from the turret. The height of the turret will admit of a man standing upright, and it must be spacious enough to permit the sentry or sentries within to handle his or their fire-arms without any incumbrance. The turret may have any desired shape, but I prefer a circular form.

Fig. 4 shows a device by which the turret may be raised or lowered.

L is a vertical support, on which the turret rests.

I' is a pulley, secured to the vertical support L, a little below the floor of the turret.

M is a lever, with one end bearing on the lower part of pulley L, and its other end is provided with a weight, O, and secured to the middle deck by a hook or strap, P.

The adjustable turret may be lowered so far down that its upper surface is level with the surface of the upper deck. The lowering of the turret is accomplished by the following method:

The hook or strap P being withdrawn, the turret then descends. As the weight O does not quite counterbalance the weight of the turret, the descent will be performed in a few seconds, (the distance of lower-

ing or raising the turret being limited to about two feet,) without any exertion and expenditure of labor. The lever M will turn on its fulerum N, and the turret will descend until it rests on the projecting ridge I' which fits into a recess, A', cut for that purpose in the upper deck. When it rests in the recess A', its upper surface will be on a level with the surface of the deck.

The upper part of the turret may be provided with a coating of caoutchouc, which would fit snugly in the recess cut in the upper deck, and prevent water from penetrating.

Speaking-tubes might be used, and serve to place the sentry in the movable turret in communication with the commander of the ship.

I do not claim the device, here employed, to raise or lower the adjustable turrets; but

What I claim, and desire to secure by Letters Patent, is—

A turret, so supported as to permit its elevation and depression, substantially in the manner and for the purpose set forth.

JOHAN LINNEMANN.
